UNITED STATES PATENT OFFICE.

GEORGE W. DICKERSON, OF NEW CASTLE, DELAWARE, ASSIGNOR TO GEORGE DRAPER & SONS, OF HOPEDALE, MASSACHUSETTS.

BOBBIN-SUPPORTER FOR SPOOLING-MACHINES.

SPECIFICATION forming part of Letters Patent No. 312,710, dated February 24, 1885.

Application filed February 29, 1884. (No model.)

To all whom it may concern:

Be it known that I, GEORGE W. DICKERSON, of New Castle, county of New Castle, and State of Delaware, have invented an Improvement in Bobbin-Supporters for Spooling-Machines, of which the following description, in connection with the accompanying drawings, is a specification, like letters on the drawings representing like parts.

10 This invention has for its object to improve the means for holding the gravitating arms of the bobbin holders or supports for spooling-machines in place loosely in the carrier. The carrier is provided with a socket to receive parts of the arms, and the latter, placed in the said socket, are held therein by a metal cap which I have devised, it having two rings or 15 projections to overlap portions of the said arms, the said cap being held in place by a pin extended through the carrier and crossing the cap, as will be described, such construction enabling me to quickly and cheaply form a cap from wrought metal which shall be very light and quickly applied without the 20 necessity of screws.

25 Figure 1 represents an under side view of a bobbin-support embodying my invention, the rest-plate for the bobbin being mostly broken off to show the cap and arms and the means 30 for holding the cap in place in the carrier; and Fig. 2 is a section of Fig. 1 on the dotted line *x x*.

The foot D, the bobbin-rest A, and gravitating arms B are substantially as usual. The carrier E is provided with a socket, *e*, to receive the portions *f* of the arms B, and these portions *f* are overlapped and loosely held in the said socket *e* by the metal cap *g*, preferably of sheet or thin metal bent to form a central groove, and two wings or grooved parts 35 each side of it, as is best shown in Fig. 2, to overlap the portions *f*. This cap is held in place by a metal pin, *h*, having a suitable head, *h'*, as shown, the said pins being inserted loosely through suitable holes in the carrier 40 E and crossing the cap.

As herein shown, I am enabled to avoid the use of screws or the cutting of screw-threads, and the cap is made very light.

I claim—

50 The carrier E and the gravitating arms B B, combined with the cap *g*, and the pin extended across the same to hold it in place with relation to the carrier, the cap holding the arms to the carrier, substantially as set forth. 55

In testimony whereof I have signed my name to this specification in the presence of two subscribing witnesses.

GEORGE W. DICKERSON.
